UNITED STATES PATENT OFFICE

169,344

BOTTLE OR SIMILAR ARTICLE

Phillip A. Sollomi, Kansas City, Mo.

Application February 13, 1953, Serial No. 23,602

Term of patent 14 years

(Cl. D58—8)

To all whom it may concern:

Be it known that I, Phillip A. Sollomi, a citizen of the United States, residing at Kansas City, in the county of Jackson and State of Missouri, have invented a new, original, and ornamental Design for a Bottle or Similar Article, of which the following is a specification, reference being had to the accompanying drawings, forming part hereof.

In the drawings:

Fig. 1 is a front elevational view of a bottle or similar article showing my new design.

Fig. 2 is a side elevational view thereof.

Fig. 3 is a top plan view.

I claim:

The ornamental design for a bottle or similar article, as shown.

PHILLIP A. SOLLOMI.
